(57) **CLAIM**

The ornamental design for a half-gallon bottle with integral handle, as shown and described.

DESCRIPTION

FIG. 1 is a front elevation view of a half-gallon bottle with integral handle according to the present invention;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a right-rear elevation view thereof;

FIG. 8 is a front-right elevation view thereof; and,

FIG. 9 is a top perspective view thereof.

The broken lines in the drawings illustrate the portions of the half-gallon bottle with integral handle that form no part of the claim.
